UNITED STATES PATENT OFFICE.

IRVING K. WALTON, OF WILMINGTON, DELAWARE.

SLIDING CAR-DOOR.

No. 799,812.

Specification of Letters Patent.

Patented Sept. 19, 1905.

Application filed December 29, 1904. Serial No. 238,812.

To all whom it may concern:

Be it known that I, IRVING K. WALTON, a citizen of the United States, residing at Wilmington, in the county of Newcastle, State 5 of Delaware, have invented certain new and useful Improvements in Sliding Car-Doors, of which the following is a specification, reference being had therein to the accompanying drawings.

10 This invention relates to a sliding car-door, and particularly to means for inserting said door in position and retaining it when the car is to be closed.

15 The invention has for an object to provide a novel construction and arrangement of operating-levers mounted upon the door and coöperating with the car structure by which both the bottom and top of the door are simultaneously forced inward as the door is 20 closed and withdrawn from such position in the opening of the door, thus securing ease of operation and an accurate fitting of the door into position.

25 Other and further objects and advantages of the invention will be hereinafter set forth and the novel features thereof defined by the appended claims.

30 In the drawings, Figure 1 is a perspective showing in full lines the door in closed position and in dotted lines the open position of the door; Fig. 2, a vertical section upon the line 2 2 of Fig. 1; Fig. 3, a horizontal section, upon an enlarged scale, upon the line 3 3 of Fig. 2; Fig. 4, a detail enlarged view of the 35 upper portion of Fig. 2; Fig. 5, a similar view of the lower portion thereof, and Fig. 6 a detail perspective of the system of operating devices carried by the car-door.

30 Like letters of reference refer to like parts in the several figures of the drawings.

The letter A designates a car of any suitable construction which is provided with the usual construction of door A', mounted to slide thereon by means of a track or way A², 45 from which a hanger A³ extends downward and is connected by a pivotally-mounted link A⁴ with the door at A⁵ and with the hanger at A⁶, so as to permit an inward movement of the door into its closed position.

50 The hanger A³ is provided with a suitable roller A⁷, adapted to travel upon the track A². The construction of hanger and track herein shown is a desirable form; but any other construction may be used, as found 55 most desirable. The door is thus carried from its open position (shown by dotted lines

in Fig. 1) into alignment with the door-opening, when it is forced inward into the position shown by full lines in Fig. 1 by means of the operating devices mounted upon the door. 60 These devices comprise a main rock-shaft B, carrying upon its lower end a crank-arm B', adapted to engage within a flanged keeper B², mounted upon the side of the car, the travel of the door being limited at this point 65 by the end wall B³ of the keeper. The rock-shaft B is pivotally mounted upon the door in any desired manner—for instance, by bearing-brackets, as herein shown—and is provided upon its upper end with a laterally-extending arm B⁴, by which the rock-shafts C for the upper portion of the door are operated. These shafts are each provided at their lower ends with a laterally-extending arm C', which arms are pivotally connected to 75 the opposite ends of the bar C² and this bar operatively connected to the arm B⁴ by means of a link C³, which permits the bar and arm C' to lie in close contact with the face of the door whenever the operating-lever B⁵, 80 carried by the rock-shaft B, is thrown into contact with said door. This operating-lever is secured to the rock-shaft and may be held in its opened or closed position by any desired means—for instance, the pin and 85 staple shown at B⁶.

The upper free ends of the rock-shafts C are each provided with a crank-arm C⁴, which operates simultaneously with the crank-arm B' to draw both the bottom and 90 top of the door inward simultaneously by engagement with their coöperating keepers. The crank-arms C⁴ are engaged beneath keepers C⁵ and C⁶, the latter being provided with an end wall C⁷ to limit the longitudinal 95 travel of the crank-arm engaging the same, while each of the keepers is provided with a slotted upper surface C⁸ to permit the upward travel of the crank-arm in shifting the door inward into its closed position, which 100 travel is due to the pivotal mounting of the door by means of the crank A⁴, as shown by full and dotted lines in Fig. 4. When the door is opened into the position shown by dotted lines in Fig. 1, it may be retained in 105 that position against any longitudinal play in the movement of the cars by means of any desired catch device—for instance, the head D upon the door adapted to engage the spring-catch D' upon the body of the car. 110

In the operation of the invention it will be seen that the door will be shifted from the

dotted-line position in Fig. 1 until the crank-arms engage the end walls of the keepers, which limit its reciprocation, at which time the operating-lever carried by the main rock-shaft will be shifted from its position at the left thereof to the position shown in full lines at the right, thus rotating this shaft, and thereby operating the respective crank-arms to simultaneously force inward both the top and bottom of the door. This construction and arrangement prevents the usual necessity of raising the door by hand to swing it into locking position, as the lower crank-arm coöoperating with the upper ones exerts this raising tendency through the pressure upon the keepers carried by the car-body. When the door is to be opened, it is only necessary to reverse the position of the operating-lever, which shifts the rock-shaft and crank-arms into the position shown in Figs. 4 and 5, thus through the arms causing the door to swing outward into the same vertical plane as the hanger and allow it to travel free of the side of the car into the open position. (Shown by dotted lines in Fig. 1.)

It will be obvious that changes may be made in the details of construction and configuration without departing from the spirit of the invention as defined by the appended claims.

Having described my invention and set forth its merits, what I claim, and desire to secure by Letters Patent, is—

1. In a device of the class described, a car-body provided with a door-opening, a door mounted to travel thereon, a hanger for said door having a link connection at its upper portion to effect a swinging movement of the door toward and from the body, keepers upon the car-body above and below said door, a rock-shaft constructed and arranged to operate crank-arms simultaneously engaging the keepers above and below the door, and said keepers being constructed to permit a vertical travel therein of the crank-arms.

2. In a device of the class described, a car-body provided with a door-opening, a door mounted to travel thereon, a hanger for said door having a link connection at its upper portion, a plurality of keepers upon the car-body above the door, a keeper below said door-opening, a plurality of rock-shafts constructed and arranged to operate crank-arms simultaneously engaging the keepers above the doors, a rock-shaft and crank-arm to engage the lower keeper, an end wall to one of the upper keepers to limit the longitudinal travel of the crank-arm therein, and an operating-lever carried by said rock-shaft.

3. In a device of the class described, a car-body provided with a door-opening, keepers arranged above and below said opening, a door mounted to reciprocate on said body,

parallel rock-shafts at the upper portion of 65 said door provided with crank-arms to engage the keepers at that point, a main rock-shaft intermediate of the parallel rock-shafts and adapted to engage the keeper at the lower portion of the door, and means for connecting said rock-shafts for simultaneous operation.

4. In a device of the class described, a car-body provided with a door-opening, keepers arranged above and below said opening, a 75 door mounted to reciprocate on said body, parallel rock-shafts at the upper portion of said door provided with crank-arms to engage the keepers at that point, a main rock-shaft intermediate of the parallel rock-shafts 80 and adapted to engage the keeper at the lower portion of the door, a laterally-extending bar from each of the parallel rock-shafts, a connecting-bar between said arms, and a connection from said bar to the main rock-shaft.

5. In a device of the class described, a car-body provided with a door-opening, keepers arranged above and below said opening, a 90 door mounted to reciprocate on said body, parallel rock-shafts at the upper portion of said door provided with crank-arms to engage the keepers at that point, a main rock-shaft intermediate of the parallel rock-shafts 95 and adapted to engage the keeper at the lower portion of the door, a laterally-extending bar from each of the parallel rock-shafts, a connecting-bar between said arms, a laterally-extending bar from the main rock-shaft, and a pivoted link connection between said 100 last-mentioned arm and the connecting-bar.

6. In a device of the class described, a car-body provided with a door-opening, keepers arranged above and below said opening, a door mounted to reciprocate on said body, 105 parallel rock-shafts at the upper portion of said door provided with crank-arms to engage the keepers at that point, a main rock-shaft intermediate of the parallel rock-shafts and adapted to engage the keeper at the lower portion of the door, a laterally-extending bar from each of the parallel rock-shafts, 110 a connecting-bar between said arms, a laterally-extending bar from the main rock-shaft, a pivoted link connection between said last- 115 mentioned arm and the connecting-bar, an operating-lever secured to said main rock-shaft, and a traveling hanger for said door provided with a link connection to permit an inward and upward movement of the door 120 into closed position.

In testimony whereof I affix my signature in presence of two witnesses.

IRVING K. WALTON.
